METHOD OF MAKING PRINTING DEVICES

Erhard U. T. Berthelsen, Euclid, Ohio, assignor, by mesne assignments, to Addressograph-Multigraph Corporation, Cleveland, Ohio, a corporation of Delaware

Application January 24, 1934, Serial No. 708,133

19 Claims. (Cl. 153—2)

This invention relates to an improved method of making printing devices comprising individual members which may carry printing lines. These members may be holding frames on which there may be mounted removable printing plates, which in turn carry embossed type; or it is possible to use my new method to form members which are to have printing characters embossed directly thereon, thus eliminating the intermediate printing plates. In either case the embossed characters are adapted to cooperate with a platen mechanism to print onto a suitable sheet.

Heretofore it has been the practice to form sheet metal printing frames or members in a series of operations, each independent of the others. A roll of metal strip was fed into a stamping machine and one of the first acts was to sever a blank from the strip of suitable size to furnish material to complete the member as successive operations were performed. Thus, during all the forming process after this severance from the strip, the only guiding support effective with respect to the partially formed plate had to be active within the confines of an area, but little larger than the area of the completed frame.

Such a restriction of the guiding action was unsatisfactory, as it prevented the maintenance of the blank being formed in rigid alignment with the die, as successive stamping operations were performed. This, in turn, meant that two produced plates might have considerable variation between certain of their respective dimensions, and further, and more important, that one plate might be and often was so inaccurately formed as to render it of uncertain accuracy in printing, or even entirely useless.

My improved method overcomes the disadvantages of inaccuracy hitherto encountered in making such address printing devices. Instead of severing the individual blank from the supply roll immediately, I retain each blank as a portion of the strip from the supply roll for as large a number of operations as possible.

Thus, that portion lying between the dies of the stamping machine may represent several printing devices, each in a different stage of formation, the portion at the end of the strip being most nearly completed, while the portion of the strip just entering between the dies is ready to receive the first forming operation. The intermediate portion of the strip discloses successive operations, each tending to further complete the device.

55 Retaining the partially formed device in one

piece for as long as possible, permits a guiding means between the dies, which more firmly positions the work for the successive operations and insures greater accuracy than was hitherto possible.

In a preferred apparatus for use in carrying out my method of manufacture, I incorporate three types of strip guiding means, namely, rollers stationary on the machine bed to guide the work therebetween; stationary guides located within the confines of the work to guide it as it moves along, and movable stop-mechanism in the nature of camming lugs. This latter mechanism may engage successive notches, cut by the die in the sides of the strip, to accurately position the strip after each feeding operation.

At a certain stage of the progressive movement of the supply strip through the die, it becomes necessary to sever the frame from the strip in order that the edges transverse of the strip may be properly formed. From this point on numerous guides in the form of camming lugs may successively engage the edges of the partially formed device and move it along as the remaining operations of forming are performed by succeeding portions of the die, until the completed member is discharged.

One of the objects of my invention is to enable the production of printing devices so accurately and uniformly formed that the embossed characters or the printing plate may be precisely located thereon. Such accuracy is very important, for instance where the matter printed must often be located within definite confines which closely bound the printing. Examples of this are where the imprint must be within a given space surrounded by other printed matter, or where figures must align in columns.

Still another object of my invention is to provide a method of forming a printing member and the ribs which guide it on the printing bed, in such manner that the ribs are always equally spaced and properly positioned with respect to the rest of the member. This accuracy in the rib location insures an accurate alignment between the printing bed and the embossed type carried by the member.

A still further object of my invention is to provide accurate mountings in the member for an index card and an index tab. These mountings, using my improved method of manufacture, can be located very definitely, and hence positively position the card and tab.

Other objects of my improved method of manufacture will become apparent hereafter, as dis-

closed in the specification which follows, and as is illustrated by the accompanying drawings. In these drawings, holding frames for carrying separate embossed printing plates are shown, but the same method may be employed where no separate printing plate is used but the frame is to be directly embossed with printing characters. It will be convenient, however, in the following specific description, to refer to the devices of the drawings as "holding frames". The novel feature of my invention will be set forth in the claims.

Referring now to the drawings, Fig. 1 is a side elevation indicating a stamping machine which I may employ and a roll of metal ribbon being fed thereto; Fig. 2 is a composite plan, showing the various forms taken by an address frame during the stages of its manufacture by my process; Fig. 3 is a plan of the completed address frame; Fig. 4 is a similar plan, but having a printing plate; an index card and two index tabs mounted on the frame; Figs. 5 to 8, inclusive, are transverse sections of the strip or portions thereof at successive stages, as indicated by the correspondingly numbered lines on Fig. 2, Fig. 7, showing also a guiding means mounted on the stamping machine bed; Figs. 9 and 10 are sections lengthwise of the strip of several portions thereof, as indicated by the lines 9-9 and 10-10, respectively, on Fig. 2; Fig. 11 is a longitudinal section, through a printing frame and plate as indicated by the line 11-11 on Fig. 4; Fig. 12 is a transverse section through the frame, index card, tab and plate, as indicated by the line 12-12 on Fig. 4.

A stamping machine, such as may be used in my improved method, is indicated at 20 in Fig. 1, and comprises a base portion 21 and a head 22, adapted to reciprocate toward and away from the base. An upper die 24 and a lower die 25 are indicated. One pair of dies may accomplish the entire forming process, or, if desired, more may be used, all mounted on the base and head and operating as a unit. A roll of sheet metal 26 of the proper width to form a completed frame, is mounted on suitable supports 27. A strip 30 comes from the roll and is led through a suitable straightening and feeding mechanism 31 which feeds the strip into the dies of the machine by intermittent steps.

While all of the different operations of the dies about to be explained take place simultaneously, it is convenient to refer to the different actions as steps in the gradual transformation of a given area of the strip. That is, once the strip 30 has been fed into the dies far enough so that the last step may be performed upon it, then with every actuation of the press every die operation takes place, though on material in successively nearer complete formation, and every time the dies are separated a completed frame drops off at the finish end.

The first function to be performed on the strip as it enters the dies, is the forming of the end notches 32 and U-slits 33. This is done at what we may call stage A. The strip then moves on between the dies until it reaches stage B. No further forming of the plate takes place here, but suitable guides 35 engage themselves with the previously cut notches 32. These guides move vertically in the press immediately after the feeding mechanism becomes inactive and before the dies become active move out of engagement with the mating notches before the feeding mechanism is next active and after the dies have

completed an operation. After the next feeding operation is complete, these guides 35 move into the next succeeding pair of notches 32 and act in this manner to retain the strip in the proper position under the dies, thus insuring that each piece will be stamped precisely as desired.

The next operation in the formation of the frame takes place at stage C. Here, slits 33 which have been previously cut, cause the formation of the outwardly extending tongue 37. This tongue, as indicated in Fig. 11, is so formed that it tends to spring upwardly out of the general plane of the frame. In addition to a main flat portion 38 of the tongue, a minor portion 39 is at the end of the tongue, parallel with it, but at a higher elevation. There results an abutment 40 at the place where the difference in elevation of these two parts of the tongue takes place. This abutment has at its center a portion 41, extending inwardly further than the adjacent portion 40, as in Fig. 3. The raised portion 39 provides means for the manual depression of the tongue to release the printing plate from the engagement of the abutment 40 and projection 41; as hereinafter more fully described.

A small, upwardly extending inwardly facing lip 43 is also formed at this stage, as well as a roughly triangular upwardly extending lip 45. This lip 45 has two of its sides 46 and 47 connected with the main frame strip 30. The third side remains open so that a card may be slid under the lip 45 to seat itself in the pocket formed by the sides 46 and 47.

The first formation of the ends of my frame is also accomplished at step C. Here, as again shown in Fig. 5, at each side of the strip a U-shaped channel 50 is formed, comprising in addition to the channel proper a flange parallel with the general strip 30 and lying a short distance below it. This formation, after later operations have been performed upon it, will comprise a rib which not only reinforces the general frame, but acts as a means for guiding the frame on the bed of a printing machine.

At step D, this channel 50 is bent from the horizontal position it assumes in step C, as in Fig. 5, until its connecting portion is normal to the general plane of the piece, as shown in Fig. 6. Each of the two channels is, of course, bent in this manner. At step D, I also form three overhanging ledges 55, all lying in a line which is perpendicular to the sides of the strip 30. These ledges extend upwardly above the frame plate and have their open portion facing the preformed tongues 37.

It is of great importance that at all times the strip 30 be properly positioned between the dies 24 and 25. For this reason a further guiding means is shown in step E. The section in Fig. 7 clearly discloses this guiding means in the form of stationary blocks 60, retained in the bed 21 by suitable screws 63, which are counter-sunk below the upper face of the guide to allow the strips to move freely over them.

As the strip 30 passes over the guides 60, the die of the stamping machine again changes the angle which the channels 50 maintain with respect to the plate and forces them to be further bent in an arc until the channels partially underlie the flat portion 30. Each of the guides 60 has an inclined portion 61, which limits the movement of the channel 50. It is, of course, apparent that as the channels 50 are moved until they come into surface to surface contact with the inclined edges 61 of the guides 60, there can be very little clear-

ance to allow sideward movement of the piece 30. What, in effect, happens is that the strip 30, which is to be guided by the members 60, is formed about the guides themselves, and thus, must of necessity, fit them very closely.

As the strip then progresses, it approaches the step F, at which place the channel 50 is completely formed, as shown in Fig. 8. This channel has now been bent through an arc of approximately 180 degrees, until it completely underlies the plate 30 and faces in the opposite direction to that it had when first formed. The reason for forming the flange 51 out of the plane of the strip 30 now becomes apparent. The corner 66 may be formed in a more rounded manner than would be possible if flange 51 did not prevent the portion 67 from lying in contact with the underside of the strip 30.

The only function taking place at the step G, 20 is the punching of three pairs of slits 70. The strip then moves on to step H, where the material between the slits 70 is formed into upwardly extending tongues 71. These tongues are well shown in Fig. 10. The sides of the tongue which 25 connect it with the plate 30 is at the opposite end of the tongue from the corresponding side of the already formed ledges 55. This is to allow an index card to lie under the ledge tongues 71 and the printing plate to lie under the ledges 55.

30 A third form of guiding means for the strip 30 is introduced at this point. It comprises a roller on each side of the strip and bearing against it. This roller 75 is mounted on the bed of the stamping machine by a suitable screw bearing 76. If desired, the roller 75 may be driven to aid in feeding a strip or it may rotate freely and act only as a guiding means in conjunction with its cooperating roller on the other side of the strip 30.

40 It is now apparent that my various guiding and locating means are adapted to accurately locate and firmly retain the strip 30 in its proper desired position between the dies of the stamping machine. Further, by the use of a long strip 30 it is 45 possible to distribute the guiding means at wide intervals along its edges, and thus obtain a far better grip than would be possible if the frame was not retained as an integral part of the strip as long as possible. I have shown three forms 50 of guiding means, all of which may be used or fewer, if desired. They may be arranged in any combination that is desired, and as many as needed employed.

The last step to be performed on the strip, as 55 such, takes place at step J. Here the edge 80 is cut. If the plate shown at step J is the first one to go through the machine, this edge will be merely trued by the die. On the other hand, if 60 various frames have preceded this one, the cut 80 marks a severance from the plate just ahead, and from this point on, the frames proceed as individuals, and not as integral parts of the strip 30.

The detached frames 100 are guided by the 65 guides similar to the guides 35 or new guide members 82 may be substituted therefor. In addition, a third guide 83 now comes into play, engaging approximately the center of the edge opposite that engaged by the guides 82 or 35, as the case 70 may be, and in this manner the frames are moved under the die faces to have the final operations performed on them.

At step L the edge 84, which has just been severed from the edge 80, is bent upwardly, as 75 indicated in Fig. 9. As the frame then proceeds

to step K, this upwardly extending flange 84 is bent over to form the ledge 85, to be used to retain the printing plate on the frame. At the same time, the opposite edge 80 is bent vertically upward, as indicated.

Step M is the last one in the formation of the completed frame. At this time, the upwardly extending edge flange is bent over to form a ledge 86 similar to the ledge 85. At this same step, a row of identical keepers 90 are formed, 10 which are used to retain the index tab. Each of these keepers, as shown in Fig. 12, comprises three parts. The keeper proper 90, under which an index tab lies, and the flat portions 91 and 92, which lie on the other side of the index tab, 15 retaining it firmly above them and below the keeper proper.

The completed frame is shown in Fig. 3. On the rear face of the frame 100 are the rib guides 58 extending along the transverse edges of the 20 frame. On the face shown are the overlying ledges 85 and 86, which act in conjunction with the ledges 55 and the tongues 71, respectively, to retain a printing plate and an index card. Spring 25 tongues 37 are also present, as are the auxiliary lips 43 and 45. A row of keepers 90 lie adjacent one another near the ledge 86 at the top of the plate.

Fig. 4 shows the same frame, but with the index 30 tab and card and the printing plate mounted thereon. Two tabs 105 are shown, occupying two of the keepers 90. The tab is formed with a wider upper portion for indexing purposes and a narrower shank to fit the keeper. The index card 110 lies under the ledge 86 and the lips 71, being 35 retained at the opposite sides by the corner pocket 45 and the small lip 43. To mount such an index card, it is merely pushed over the lip 43 and under the ledges and lips 86, 71 and 45, and then sprung under the lip 43.

40 Adjacent the card index is the printing plate 115. At its long edges, this plate is serrated as shown at 116, to facilitate its placement on the frame by sliding it over the spring tongue 38 and under the ledges 55 and 85. At each of the shorter 45 edges, spring tongue 37 retains the plate against longitudinal movement, by virtue of the fact that its abutment 40 is raised by the spring action to abut the edge 117. The inwardly extending portion of the abutment 40 fits closely into mating 50 notches of the plate 115 and aids in preventing transverse movement of the plate 115. The movement parallel with the long edges of the frame, as has been stated, is prevented by the abutments of the spring tongues 38.

55 The plate 115 is adapted to have embossed thereon raised type characters 120. These characters may be in the form of a name and address or may convey any other meaning desired, such, for instance, as dividend data for stock certificates. The index card 110 may contain a transcript of the characters on the plate 115 or any other material suitable for proper indexing. The tab 105, if used, may be placed in any keeper desired, to give a visual indication of the class of 60 the subject-matter on the plate, or to be acted upon by suitable selecting mechanism in the printing machine to cause the plate carrying the tab in this position to be either printed or skipped, as determined by the setting of the machine.

70 From the foregoing description, it will be apparent that I have devised an efficient method which is of great advantage in accurately forming plate-like printing devices. Due to the fact that I retain each individual blank as an integral part 75

of a strip for as long as possible, I am able to furnish a long edge against which my guiding means may bear, and accordingly position the blank between the dies with great accuracy.

5. This greater accuracy in positioning the work in the dies results in a more perfect product. Furthermore, I secure such accuracy that a printing plate may be retained on a holding frame with sufficient precision to eliminate any movement of the one with respect to the other. The result is that when such plate is being used to print, no movement of the embossed characters can take place to move them either out of line before the printing starts, in which case a misplacement of the printing would result, or to move them out of line while the printing is taking place, in which case a blur might be caused.

10. The index tab keepers are accurately located on the device, so that there is no danger that the tab will fail to function at any time during its use, and the index card is properly held at all times. Still further, I am enabled to produce the guiding ribs truly and accurately and thus to retain the device in the printing bed guide channels, not only in better alignment, but with the certainty that the printing characters will be in proper registration with the printing bed.

I claim:

1. The method of making printing devices comprising passing a metal strip of a width approximately equal to the length of a long edge of said device, by intermittent steps through forming dies, and locking said strip at its edges by means positively preventing longitudinal movement of the strip.

2. The method of making devices of the character described, comprising passing a metal strip through dies, said dies being so placed that the action of each pair will further the plate formation as done by the next preceding pair, each pair of said dies acting within an area substantially equal to the area of a completed device, several of such pairs of dies acting simultaneously on a portion of said strip which remains integral and a plurality of pairs of the dies acting at the same operation on severed portions of the strip.

3. The method of making plate-like printing devices, comprising passing a metal strip through dies, said dies being so placed that the action of each pair will further the plate formation of the next preceding pair by a series of consecutive and simultaneous operations, forming the edges of each device which are parallel with the edges of the strip while the blanks remain integral parts of said strip, subsequently severing said blanks from said strip while the strip is guided by the reformed edges, and then forming the severed edges of the members.

4. The method of making devices of the character described, which comprises passing a substantially continuous metal strip between a series of pairs of dies, each pair of dies operating on the formation of the next preceding pair, several of said operations being performed on integral parts of said strip, one pair of said dies acting to overturn opposite edges of said strip, thereafter guiding said strip with means bearing outwardly against such overturned edges.

5. The method of making printing devices, comprising performing a plurality of operations sequentially on different portions of a substantially continuous strip before said portions are severed from the strip, notching the opposite edges of said strip in one of said operations, feeding the strip a distance required for one device,

and subsequently guiding said strip by means engaging said notches while performing subsequent operations on the strip.

6. The method of making printing devices, comprising guiding a substantially continuous strip of metal between a series of pairs of aligned dies adapted to form said devices by a series of successive actions, each die performing a different operation on said strip, intermittently progressing said strip a distance equivalent to that required for one device, whereby each partially formed blank is consecutively engaged by each pair of dies while remaining an integral part of said strip, such blanks being subsequently severed from said strip but advanced with the strip in the same direction as the strip and being engaged by further dies which change the shape of the severed portion without changing its location in the direction of the strip.

7. The method of forming printing devices including means for notching the opposite edges of a substantially continuous strip at regular intervals, engaging the formed notches with a guide to rigidly hold said strip from movement either longitudinally or transversely, forming the strip while said guide is active, and simultaneously severing an individual partially formed blank from said strip.

8. The method of forming printing devices including means for notching a substantially continuous strip at regular intervals, engaging the formed notches with a guide to align said strip longitudinally and transversely, forming the strip while said guide is active, simultaneously severing an individual partially formed blank from said strip, and forming a series of index keepers adjacent a severed edge of such blank while it abuts guides in the region of the notched areas.

9. The method of forming printing devices, comprising intermittently feeding a substantially continuous strip between a series of pairs of dies a distance substantially equivalent to the length of material required for one device, each of said pairs of dies being substantially as large as a completed device, one of said pairs of dies acting to cut notches in opposite edges of said strip, another of said dies acting to turn the edges of unsevered portions of the strip between the previously formed notches and while other integral portions of the strip are being notched, guiding and locating said strip by engaging said notches and said turned edges while other integral portions of the strip are being acted on.

10. The method of forming printing devices comprising intermittently feeding a substantially continuous strip between a series of pairs of dies, a distance substantially equivalent to that required for one device, each of said pairs of dies being substantially as large as a completed device, the first pair of said pairs of dies coacting to cut notches in opposite edges of said strip, thereafter guiding and locating said strip by engaging said notches while another pair of said dies act to turn the edges of the strip between notches and while other integral portions of the strip are being notched, guiding and locating said strip by engaging the last formed notches and the last formed turned edges, said guiding and locating means acting to retain the strip in position while the dies are forming notches in unnotched portions of the strip and turning the edges of previously notched portions of the strip, and subsequently severing the partially completed device from the strip.

11. The method of forming holding frames for

printing plates, comprising intermittently passing an integral strip between a series of dies each die acting over substantially the same area as a finished frame, said dies acting in succession to notch the outer edges of said strip for forming spring tongues on said strip, and to form abutments on the previously formed spring tongues, while the strip is positioned and retained in position by means engaging said notches, and subsequently severing a frame from the positioned strip in the area of said notches while the strip is retained in position by means engaging said notches.

12. The method of forming holding frames for printing plates, comprising intermittently passing an integral strip between a series of dies, each die having substantially the same area as a finished frame, said dies acting in succession to notch the outer edges of said strip to form spring tongues on said strip, to next form abutments on the previously formed spring tongues, to then overturn the edges of the strip between previously formed notches to form flanges embodying inwardly facing and downwardly extending channels running lengthwise of said strip, to bend said channels inwardly along the face of said strip forming downwardly extending ribs, each of said operations being performed on different integral portions of said strip simultaneously, positioning and retaining said strip in accurate position relative to the dies by engaging said notches and said inturned flanges and the edges of said rib at spaced intervals, subsequently severing a frame from the positioned strip in the area of said notches, subsequently positioning the severed frame by means abutting the notched surface thereof and forming keepers to receive index tabs on said frame while so positioned.

13. The method of making individual devices from a continuous strip in different operations, which comprises retaining the partially formed blanks as integral portions of said strip for several operations, guiding said strip during these operations, severing a forward portion of the strip, advancing the severed portion in the same direction as the connected strip, and simultaneously acting on the connected strip, and bending the rear and forward edges of the severed portion while maintaining the body of the severed portion substantially planar.

14. The method for making a device of the class described, comprising performing a plurality of related forming operations simultaneously on a connected strip, as such strip is fed through the region in which the operations are performed, successively severing said strip to make a plurality of individual units but retaining said units in alignment with said strip and simultaneously forming both the connected strip and the plurality of individual units.

15. The method of forming individual devices, comprising intermittently feeding a substantially continuous strip between a series of pairs of dies a distance substantially equivalent to the length of material required for one device, one of said pairs of dies acting to cut notches in opposite edges of said strip, another of said dies acting to turn the edges of unsevered portions of the strip between the previously formed notches and while other integral portions of the strip are being notched, guiding and locating said strip by engaging said notches while other integral portions of the strip are being acted on.

16. The method of forming individual devices, comprising intermittently feeding a substantially continuous strip between a series of pairs of dies, a distance substantially equivalent to that required for one device, one of the pairs of dies coacting to cut notches in opposite edges of said strip, thereafter guiding and locating said strip by engaging said notches while another pair of said dies act to turn the edges of the strip between notches.

17. The method of forming holding frames for printing plates, comprising intermittently passing an integral strip between a series of dies, said dies acting in succession to form spring tongues on said strip, and to form abutments on the previously formed spring tongues, subsequently severing a frame from the strip, and bending over the edge of the frame along the line of severance.

18. The method of making individual devices, comprising guiding a substantially continuous strip between a series of pairs of aligned dies adapted to form said devices by a series of successive actions, each die performing a different operation on said strip, intermittently progressing said strip a distance equivalent to that required for one device, whereby each partially formed blank is consecutively engaged by each pair of dies while remaining an integral part of said strip, severing the endmost partially formed blank from the advance end of said strip, and bending the rear edge of the severed unit while maintaining said unit in the plane of the strip and at the same operation which forms a previous portion of the continuous strip.

19. The method for making a printing device, comprising performing a plurality of different forming operations on united portions of a metal strip simultaneously, including reducing the extreme width of the strip, and progressively guiding said strip from a region where one operation is performed to the next region by guiding means engaging the reformed edges after such reduction in width.
